Application March 14, 1957, Serial No. 45,262

Term of patent 14 years

(Cl. D15—8)

FIG. 2

FIG. 3

Figure 1 is a front perspective view of a ladder showing my new design, a portion thereof is broken away for convenience of illustration and to indicate indefinite length;

I claim:

The ornamental design for a ladder or the like, as shown and described.
